UNITED STATES PATENT OFFICE.

ISAAC N. MARQUIS, OF ROSEDALE, KANSAS, ASSIGNOR TO JAMES H. HOLMAN AND CHARLES C. GESICK, OF KANSAS CITY, MISSOURI.

DESIGN FOR A VAPOR-BURNER.

SPECIFICATION forming part of Design No. 33,587, dated November 20, 1900.

Application filed August 22, 1900. Serial No. 27,733. Term of patent 7 years.

To all whom it may concern:

Be it known that I, ISAAC N. MARQUIS, a citizen of the United States of America, residing in Rosedale, in the county of Wyandotte and State of Kansas, have invented and produced a new and original Design for Vapor-Burners, of which the following is a specification, reference being had to the accompanying drawings, forming a part thereof.

Figure 1 represents an elevation view of a vapor-burner shown in my design. Fig. 2 represents a plan view, and Fig. 3 represents a cross-section on the line *a b* of Fig. 1.

The leading or material feature of my design consists in the configuration of the burner. The base portion *A* is in the form of a horizontal disk from which the body *B* rises vertically. The upper end of the body *B* is in the form of a hollow cylinder superposed upon the middle section *C*, the shape of which is best shown in Fig. 3. That portion of the middle section *C* to the left of the dotted line *c d* is semicylindrical and is concentric with but of smaller diameter than the upper part of the body *B*. The right side of the middle portion *C* is as follows: The extreme right wall *D*, as shown in Fig. 3, is of the same shape as the upper portion of the body *B* and is described from the same radius and is joined with the circular portion to the

left of the dotted line *c d* by the two slightly-converging straight lines *E*. The middle section *C* connects with the upper portion of the body *B* by a curved flaring portion *F*, as shown in Fig. 1. From the under side of the base *A* and concentric therewith is a cylindrical boss *G*, from the right side of which extends at right angles a partially cylindrical boss *H*, from the upper side of which projects vertically a hollow semicylinder *I*, separated 35 a short distance from the right wall of the body of the burner. Located concentrically with and disposed below the boss *G* is the vertical cylindrical jet portion *J*, the right side of which, near its upper end, is connected with 40 the under side of the boss *H* by an inclined cylindrical bridge *K*.

Having described my invention, what I claim as new, and desire to secure by Letters Patent, is—

The design for a vapor-burner, as herein shown and described.

In testimony whereof I have signed my name to this specification in the presence of two subscribing witnesses.

ISAAC N. MARQUIS.
